UNITED STATES PATENT OFFICE.

HALFDAN A. STEEN, OF NORWOOD, OHIO, ASSIGNOR, BY MESNE ASSIGNMENTS, TO
ALLIS-CHALMERS MANUFACTURING COMPANY, A CORPORATION OF DELAWARE.

CIRCUIT-BREAKER.

1,211,778.

Specification of Letters Patent.

Patented Jan. 9, 1917.

Application filed March 23, 1912. Serial No. 685,715.

To all whom it may concern:

Be it known that I, HALFDAN A. STEEN, a subject of the King of Norway, residing at Norwood, in the county of Hamilton and State of Ohio, have invented certain new and useful Improvements in Circuit-Breakers, of which the following is a full, clear, and exact specification.

My present invention relates to circuit-breakers.

In modern high potential electrical transmission systems special protective apparatus is required, as the ordinary circuit-breakers are not adapted to provide a separation between their terminals sufficient to break the arcs which form. Moreover, the ordinary circuit-breaker is so slow in acting that it allows current to continue long enough to defeat the object of the circuit-breaker.

It is the object of my invention to provide an arrangement whereby, under abnormal conditions, an electric circuit will be interrupted sufficiently quickly and by a break sufficiently wide to prevent a continuance of the current for any appreciable time.

It has been found that the pressure generated by the blowing of an inclosed fuse is almost explosive in its nature, the pressure instantaneously produced in the fuse chamber often being enormous. In my device I aim to use the pressure suddenly developed by this blowing of the fuse to move to off position a switch arm which normally engages stationary contacts for completing a circuit, thus obtaining an almost instantaneous interruption of the circuit.

The various novel features of my invention will be apparent from the description and drawings, and will be particularly pointed out in the claims.

This invention is illustrated in the single figure of the drawing, which is a side elevation partly in section, of the preferred form.

Mounted upon a suitable insulating panel or support 10 are two stationary contacts 11 and 12 which are normally connected by a movable switch arm 13. This movable switch arm 13 is preferably pivotally mounted in the stationary contact member 11. The main body portion of this movable switch arm comprises an insulating member 14 having a hollow portion 15 and an opening 16 which is formed in the curved projection 17 of said member 14. This in-

sulating member is provided at its ends with threaded portions 18 and 19 by means of which metal caps 20 and 21 are secured thereto. The metal cap 20 is provided with a projection 22 which forms the pivotal connection at 23 with the stationary switch contact 11, and the metal cap 21 is provided with a knife blade projection 24 which normally engages the stationary contact 12. Interposed between each cap and the ends of the insulating member 14 are metal disks 25 which are in electrical contact with the metal caps and to which a fuse 27 is electrically connected, by any suitable means, such as solder 26. This fuse occupies the central portion of the hollow switch arm 13, and forms an expulsion fuse. Adapted to receive the curved projection 17 and to normally close or cover the opening 16 is a curved socket member 28 which is secured to the panel 10.

When the movable switch member 13 is in its normal position, as here illustrated, with the movable contact member 24 engaging the stationary contact member 12, the circuit is completed through terminal 29, stationary contact 11, projection 22 of cap 20, lower metal disk 25, fuse 27, upper metal disk 25, knife blade contact 24 of cap 21, stationary contact 12 and terminal 30.

In case of an overload, whether the current be alternating, pulsating, or direct, the fuse 27 blows. Since the fuse is in the comparatively small space of the hollow movable switch arm 13, which has but one main outlet or opening 16, a comparatively great pressure is generated by the blowing of the fuse and exerts itself through this opening upon the socket member 28, violently forcing the movable contact member in a counter-clockwise direction and out of engagement with the stationary contact member 12. This movement of the movable switch member in a counter-clockwise direction is quickly and violently made, causing a nearly instantaneous separation between the movable switch member 13 and stationary contact 12. This separation is great enough to prevent any continuance of the current and sudden enough to prevent any damage before the circuit-breaker has operated. In order to prevent any damage to the movable switch arm 13, a buffer spring 31 is provided to catch said switch arm.

There may be various modifications in the precise arrangement here shown and described, and I intend to cover all such modifications which do not involve a departure from the spirit and scope of my invention as set forth in the appended claims.

What I claim as new is:

1. In a circuit breaker, the combination of fixed contacts, a movable switch arm normally engaging said contacts, said switch arm having a hollow portion with an opening, stationarily mounted means effective to cover said opening when said switch arm is in circuit-closed position, and a fuse in the hollow portion of said switch arm, pressure created on the blowing of said fuse acting against said covering means to throw said switch arm out of engagement with one of said contacts.
2. In a circuit breaker, the combination of fixed contacts, a movable switch arm adapted to engage said contacts, said switch arm including a hollow member provided with a projection having an opening, means for telescopically receiving said projection and covering said opening, said means being mounted on a stationary support, and a fuse in the hollow portion of said switch arm, pressure created by the blowing of said fuse acting against said means to throw said switch arm out of engagement with one of said contacts.
3. In a circuit breaker, the combination of a movable switch member, a fuse inclosed within said movable switch member, and means forming a stationary abutment against which fluid pressure created on the blowing of said fuse is exerted directly and reacts to cause a movement of said movable switch member.
4. In a circuit-breaker, the combination with a movable switch member having a hollow portion and provided with a curved projection with an opening, a curved member mounted on a stationary support and adapted to receive said curved projection and to cover said opening, and a fuse in the hollow portion of said switch member which when blown generates pressure which is exerted between said movable switch member and covering member for actuating said switch member.
5. In a circuit-breaker, the combination of stationary contacts, a movable switch member comprising a hollow member having an opening, metal caps for the ends of said hollow member, said caps being engageable with said stationary contacts, and a fuse in the hollow member electrically connecting said caps to complete a circuit through said stationary contacts and said movable switch member, and means for covering said opening, said covering means being mounted on a stationary support and coöperating as an abutment with said movable switch member

to utilize the pressure generated by the blowing of the fuse to cause said movable switch member to be actuated.

6. In a circuit-breaker, the combination of fixed contacts, a movable contact comprising a hollow member having a curved portion with an opening, a socket mounted on a fixed support and adapted to receive said curved portion and to cover said opening, and an expulsion fuse carried in the hollow portion of said movable contact member and which when blown generates pressure which is exerted between said movable contact and socket for actuating said movable contact.

7. In a circuit-breaker, a hollow movable switch member having a projection with an opening, a member with which said projection telescopes, said latter member being mounted on a stationary support, and a fuse in the hollow portion of said switch member which when blown generates pressure which is exerted between said switch member and member with which said projection telescopes to cause a movement of said switch member.

8. In a circuit-breaker, the combination of a hollow switch member having an opening, an element with which said switch member is operatively associated, said element being immovably mounted on a stationary support, and a fuse in the hollow portion of said switch member which when blown generates pressure which is exerted between said switch member and said element to cause movement of said switch member.

9. In a circuit-breaker, a movable switch member, said member being provided with a fuse-containing recess having an opening to the outside of said member, and a member mounted on a stationary support and adapted to cover the opening in said switch member when the latter is in one position, pressure created on the blowing of said fuse acting on said covering member to cause actuation of said switch member.

10. In a circuit-breaking device, the combination of a plurality of coöperative contacts one of which is movable toward and away from the other, supports for said contacts, the support for a movable one of said contacts comprising a hollow portion, a fuse contained in said hollow portion, an abutment carried by and immovable relatively to the support for the other of said contacts, said abutments being operatively associated with a portion of said fuse-carrying support whereby pressure created on the blowing of said fuse is exerted directly upon said abutment to cause movement of one of said contact-carrying supports relatively to the other.

11. In a circuit-breaker, a pair of coöperative, relatively movable switch members, supports for said switch members, the support for a movable one of said switch mem-

bers being provided with a fuse-containing recess having an opening to the outside of said member, and a member immovably mounted on the support for the other one 5 of said switch members and adapted to cover the opening in the support for said first switch member when the latter is in one position, pressure created on the blowing of said fuse acting on said covering member to

cause actuation of said movable switch 10 member.

In testimony whereof I affix my signature, in the presence of two witnesses.
